UNITED STATES PATENT OFFICE.

MARK ANTHONY BROWN, OF DOUGLAS, GEORGIA, ASSIGNOR OF ONE-HALF
TO WILLIAM O. PAXSON, OF DOUGLAS, GEORGIA.

CAR-COUPING.

SPECIFICATION forming part of Letters Patent No. 689,063, dated December 17, 1901.

Application filed April 11, 1901. Serial No. 55,312. (No model.)

To all whom it may concern:

Be it known that I, MARK ANTHONY BROWN, a citizen of the United States, and a resident of Douglas, in the county of Coffee and State 5 of Georgia, have invented new and useful Improvements in Car-Couplings, of which the following is a full, clear, and exact description.

My invention relates to car-couplings, and 10 has for its object to provide a construction by means of which the coupling-pin is readily locked in its engagement with the coupling and readily detachable therefrom.

The invention will be fully described here- 15 inafter and the features of novelty pointed out in the appended claims.

Reference is to be had to the accompanying drawings, forming a part of this specification, in which similar characters of reference indicate 20 corresponding parts in both figures.

Figure 1 is a perspective view showing one end of a car provided with my improved coupling. Fig. 2 is a perspective view of my improved locking-bearing.

25 Three bearings K K and K' are alined with each other, as shown in Fig. 1. In these bearings a rocking shaft J is mounted so as to have a little longitudinal play. Firmly secured upon this shaft is an arm J', which is normally free to move radially as the shaft is rocked, which is done by means of the handles J². Upon this radial arm J' is a ring I' for the purpose of raising the coupling-pin in the usual manner. The central bearing K' 30 is provided with two transverse slots K², connected by a longitudinal passage K³ for the movement of the crank J⁸. The slots in the central bearing K' together form a Z-shaped opening, thus forming oppositely-disposed 35 lugs or shoulders K⁴ K⁵, lying in parallel planes at right angles to the general direction or axis of the rocking shaft. As the shaft is moved endwise to the right or left, the arm J' may be made to engage either of said lugs or 40 shoulders K⁴ K⁵, and thereby locked against upward movement or against downward movement, as the case may be. In Fig. 1 the arm is in the left-hand side of the bearing K', and therefore engaging the lug K⁴ and locked

against upward movement. If disengaged 50 and moved to the right-hand side of the bearing, it is locked against downward movement, being in engagement with the upwardly-facing lug K⁵. The handles J² are used for both 55 rocking the shaft and sliding the same endwise.

The letters B D' D² D³ D⁴ E E' E² E³ refer to various parts of my improved coupling and its appliances, for which I intend to file another application.

Having thus described my invention, I claim as new and desire to secure by Letters Patent—

1. A coupling device, comprising a bearing provided with a plurality of communicating 65 slots, the walls of which form a pair of lugs located in a staggering relation, and a cylindrical shaft journaled in said bearing and free to slide lengthwise and also to rock, and pro- 70 vided with a radial arm extending through said slots and engaging said lugs and also provided with a handle for rocking said shaft and sliding the same lengthwise to engage the lugs.

2. A coupling device, comprising a rocking shaft mounted in a plurality of bearings and 75 provided with a radially-disposed arm, one of said bearings being provided with two transverse slots located in different vertical planes and connected by a longitudinal passage, constituting a Z-shaped opening, through which 80 the said radially-disposed arm extends.

3. A coupling device, comprising a bearing provided with a cylindrical shaft-seat and slotted so as to form a pair of twin lugs located in parallel planes, and having oppositely-disposed bearing-faces located in a staggering relation each to the other, a cylindrical shaft journaled in said shaft-seat and free to move lengthwise, a radial arm engaging said lugs, and means for securing a coupling-pin upon said radial arm.

4. A coupling device, comprising a rocking shaft provided with an arm free to move radially in different planes, a bearing for supporting said rocking shaft, said bearing being provided with staggering lugs disposed in different planes at right angles to the length of said shaft for the purpose of limiting the

said arm to different degrees of movement in the several different planes, and means for securing a coupling-pin upon said arm.

5. A coupling device, comprising a rocking shaft mounted in a plurality of bearings and provided with a radially-disposed arm, one of said bearings being provided with two transverse slots located in different vertical planes and connected by a longitudinal passage con-

10 stituting a Z-shaped opening, through which

the said radially-disposed arm extends, and means for securing a coupling-pin upon said arm

In testimony whereof I have signed my name to this specification in the presence of 15 two subscribing witnesses.

MARK ANTHONY BROWN.
